UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

REDUCTION OF VACUUM-TUBE CAPACITANCE.

Application filed January 25, 1927, Serial No. 163,326, and in Germany February 2, 1926.

This invention relates to the reduction of vacuum tube capacitance and more particularly to a method and means for accomplishing this by arranging a plurality of tri-electrode units in series.

The specification is accompanied by a drawing in which

Figure 1 is a wiring diagram of one modification of my invention; and

Figure 2 is a wiring diagram of a more advanced modification in which the anode circuits, with relation to the direct current, are arranged in parallel.

It is a well-known fact that in the use of transmitters and receivers for very short electromagnetic waves, the self-capacitance of the tube plays an important part. The generation of extra-short waves may be rendered impossible on account of the fact that the electrode capacitance possesses such a high value that unduly large displacement currents are caused to flow across the tube.

Now, in accordance with the invention, in arrangements for short waves, two or more tubes are to be connected in series, so that the effective capacitance consists of the series arrangement of the tube capacities formed by the different tubes. Such an arrangement is shown in Fig. 1. In order to make the necessary energy available, it would be necessary for the series combination of the tube to use a higher potential than would be required for the operation of an individual tube. It is therefore recommendable, in order that the necessity of choosing unduly high working potentials may be avoided, to use for such an arrangement as hereinbefore stated tubes having high emissivity and low plate potential.

But there are also chances of using circuit arrangements in which one and the same potential source is employed for the feeding of all of the tubes. This is shown, for example, in Fig. 2. It is, of course, necessary in these connections or circuit arrangements to separate the different circuits from each other as regards the flow of direct current and radio frequency currents by the addition of conveniently proportioned choke coils and block condensers. There further arises this danger that undesirable grounds may be created for radio frequency current owing to capacitive influences, a circumstance that should be particularly kept in mind with re-

gard to the heat-supply battery. It is therefore recommendable to insert small choke coils in the heating-current leads in order to thus prevent grounding through the heating battery of the radio frequency currents.

For a better understanding of the idea underlying the invention, Fig. 2 may be described as showing a tube generator comprising two tubes denoted by R_1 and R_2 , arranged in series for radio frequency currents by way of the condenser K . Between the plate of tube R_1 and the cathode or filament of tube R_2 , is a working oscillation circuit S . The grids of the two tubes are connected with each other through the condenser c . This should be of high reactance, preferably of the order of magnitude of the tube capacitance, in order not to by-pass the lower tube. The control potential for the grids is produced by means of coupling an oscillation circuit s interposed between the grid and the filament of tube R_2 , with the working circuit S . The D. C. connection of the two tubes is effected at the battery H ; in the leads to the plates of the two tubes are the choke coils D , while chokers d are inserted in the heating circuit. Of course, a great number of different arrangements are conceivable in which the basic features of the present invention may be incorporated.

It is obvious that the invention is not limited to the use of only two tubes in series, and furthermore, that the tri-electrode units need not each be incased in a separate evacuated envelope.

I claim:

1. In combination, vacuum tube circuits, a plurality of electrode units each comprising an anode, a cathode, and a control electrode, of which, relative to the path of alternating energy, the anode cathode electrodes are connected in series, and the control electrodes are connected in parallel, and a reactance of the order of magnitude of the tube capacitance connected between the control electrodes.

2. The combination with vacuum tube circuits, of a plurality of electrode units each comprising an anode, a cathode, and a control electrode, the anode and cathode electrodes of which are connected in series for high frequency currents, while relative to the path of direct energy, the anode and cathode electrodes are connected in parallel.

3. In combination, a plurality of electrode units each comprising an anode, a cathode, and a control electrode, a source of energy, means including choke coils connecting said source to anode and cathode electrodes, means including blocking condensers connecting the anode and cathode electrodes in series, an output circuit coupled across the extreme anode and cathode of the series of electrode units, and a circuit arranged to influence the control electrodes.
4. In combination, a plurality of electrode units each comprising an anode, a cathode, and a control electrode, a source of anode current, means including choke coils connecting said source to the anode and cathode electrodes in parallel, means including blocking condensers connecting the anode and cathode

electrodes in series, an output circuit coupled across the extreme anode and cathode of the 20 series of electrode units, and a circuit arranged to influence the control electrodes in parallel.

5. In combination, a plurality of electrode units each comprising an anode, a cathode, and a control electrode, means coupling the anode and cathode electrodes in series for alternating energy, an output circuit coupled across the extreme anode and cathode of the 25 series of electrode units, a coil regeneratively 30 coupled to the output circuit and arranged to influence the control electrodes in parallel, and a condenser of the order of magnitude of the tube capacitance arranged between the control electrodes.

ALEXANDER MEISSNER.
